UNITED STATES PATENT OFFICE

171,190

AUTOMOBILE WINDOW SILL PROTECTOR

Alfred R. Blumenthal, Chicago, Ill.

Application January 2, 1953, Serial No. 22,990

Term of patent 14 years

(CL. D14—6)

To all whom it may concern:

Be it known that I, Alfred R. Blumenthal, a citizen of the United States, residing at Chicago, Cook County, Illinois, have invented a new, original, and ornamental Design for an Automobile Window Sill Protector, of which the following is a specification, reference being had to the accompanying drawing, forming a part hereof.

Figure 1 is a top view of an automobile window sill protector showing my new design. Said protector is formed of a transparent material.

Figure 2 is a bottom view thereof.

Figure 3 is an end view taken on lines 3—3 of Figure 2, and

Figure 4 is a cross sectional view taken on lines 4—4 of Figure 2.

I claim:

The ornamental design for an automobile window sill protector, as shown and described.

ALFRED R. BLUMENTHAL.
